UNITED STATES PATENT OFFICE.

THOMAS J. KOLOCOTRONIS, OF SHENANDOAH, PENNSYLVANIA.

ATTACHMENT FOR BARBERS' CHAIRS.

1,137,764.

Specification of Letters Patent.

Patented May 4, 1915.

Application filed August 30, 1913. Serial No. 787,507.

To all whom it may concern:

Be it known that I, THOMAS J. KOLOCOTRONIS, a citizen of the United States, residing at Shenandoah, in the county of Schuylkill, State of Pennsylvania, have invented certain new and useful Improvements in Attachments for Barbers' Chairs; and I do hereby declare the following to be a full, clear, and exact description of the invention, 10 such as will enable others skilled in the art to which it appertains to make and use the same.

This invention relates to improvements in chair attachments, and particularly attachments for barbers' chairs.

The principal object of the invention is to provide a simple attachment for a barber's chair, for receiving the head rest of the chair when said head rest is not in use. 20 Another object is to provide a device of this character which is arranged in a convenient position, and into which the head rest can be quickly and easily placed, and from which the same can be quickly removed 25 when the rest is desired for use.

Other objects and advantages will be apparent from the following description, when taken in connection with the accompanying drawings.

30 In the drawings: Figure 1 is a perspective view of a portion of a barber's chair showing my invention attached thereto and the head rest therein. Fig. 2 is a vertical transverse sectional view through the attachment and 35 portion of a chair.

Referring particularly to the accompanying drawings, 10 represents the bottom or seat portion of a barber's chair, and 11 the arm thereof.

40 In the use of the ordinary barber's chair, when the head rest is not in use, the same is removed from the back of the chair and placed in the most convenient spot, this usually being the shelf of the mirrors back 45 of the chairs. This is rather inconvenient, as the head rest occupies space needed for the barber's implements. To obviate the necessity for this indiscriminate disposal of the head rest, I provide an attachment for

the chair which will receive and hold the 50 rest until it is needed.

My attachment is in the form of a box, as shown at 12, which is long and comparatively shallow and narrow, one side of which carries the perforated ears 13 respectively 55 at the upper and lower middle portions thereof. The ears are so spaced apart as to receive therebetween the side edge of the bottom of the chair, suitable fastening devices, as the screws 14, being passed through 60 the openings of the ears and engaged in the edge of the chair from above and below.

As clearly shown, the upper and lower sides of the box are open to permit the quick and easy withdrawal of the head rest 15, the 65 stem 16 of the rest protruding below the box when the rest is in the box. The rear end of the box is open, and attached to the rear end of the outer side of the box, by means of the spring hinge 17 is an inwardly swinging door 18. The free edge of this door is arranged to engage with the inturned rear end 19 of the inner or attached side of the box. This inturned end prevents the door 70 swinging outwardly from the end of the box. 75

In placing the head rest in the box, the cushion portion of the head rest naturally is grasped in the hand when the same is removed from the back of the chair, and by disposing the same so that the stem 16 depends below the cushion portion, and pushing open the door with the stem, the stem will enter the box and protrude through the open bottom. Upon release of the head rest, the cushion portion will rest on the upper 85 edges of the box. In removing the head rest from the box, the same is pulled up straight through the top of the box.

What is claimed is:—

An attachment for a barber's chair comprising an elongated member open at the top and bottom and one end, for the reception of the stem of the head rest of the chair, vertically spaced parallel attaching ears extending from the inner side of the receptacle 95 and arranged for attachment to the upper and lower sides of the seat of the chair, the inner side of the attachment at the open end

thereof having an angular portion extending toward the opposite side of the attachment and forming a stop, and an inwardly opening spring hinged door carried by the outer 5 sides of the said open end and normally engaging with the said stop whereby outward movement of the door is prevented.

In testimony whereof, I affix my signature, in the presence of two witnesses.

THOMAS J. KOLOCOTRONIS.

Witnesses:

HARRY M. TEST,
GEO. H. CHANDLER.
